[57] CLAIM

The ornamental design for a bracelet, as shown and
described.

DESCRIPTION

FIG. 1 is a top plan view of a bracelet showing my new
design;

FIG. 2 is a front elevational view;

FIG. 3 is a left side elevational view;

FIG. 4 is a bottom plan view;

FIG. 5 is a fragmented view taken along the lines 5—5
of FIG. 2.

FIG. 6 is an enlarged partial view of the central portion
of the bracelet; and

FIG. 7 is a front elevational view of bracelet showing a
second embodiment of my new design.

FIG.1
